[57] ABSTRACT

A truck mounted vacuum type sweeper constructed for dual operation employs identical street cleaning apparatus on each side of the machine and an extension broom which may be swiveled from one side of the machine to the other for left hand and right hand street cleaning operations. The extension broom is mounted such that its axis of rotation is always parallel to the pavement being swept. A control system is provided for programming the operation of the machine and includes means for transferring from, for example, a left hand sweeping operation to a right hand sweeping operation by merely operating a toggle switch. The control system further includes means for automatically lifting the suction nozzles when the operator of the sweeper shifts into reverse in order to prevent damage to the nozzle supporting structure.

VACUUM TYPE SWEEPER

BACKGROUND OF THE INVENTION

1. Field of the Invention

This invention relates to truck type vacuum sweepers and is particularly concerned with vacuum sweepers which are constructed for dual operation.

2. Description of the Prior Art

Vacuum sweepers which are constructed on the chassis of a truck are well known in the art and generally include a rotating side broom which sweeps along a curb and deposits the sweepings into a large container carried by the truck by way of a vacuum nozzle which trails behind the side broom. Such vacuum sweepers are generally provided with a hydraulic system for operating the brooms, a pneumatic system for raising and lowering the street cleaning implements between a sweeping position and a transporting position, and a water spray system to aid in keeping dust at a minimum. In operation the sweeper is driven adjacent one curb and cleaning of the opposite side of the roadway must be accomplished by another machine or by making a second pass with the sweeper adjacent the opposite curb.

Dual machines make it possible to sweep or street clean either side of a roadway while traveling in one direction. Dual machines, however, conventionally have dual controls and it is common practice for the operator of a dual machine to swing from one side of the roadway to the other, either in accordance with a planned street cleaning schedule or when he notices that a portion of the opposite roadway should be swept. Heretofore, the operator of a dual machine, in order to switch over to the opposite side of the roadway, would first disengage or shut down all operating components or devices on a street cleaning side of the machine, traverse the machine to the other side of the roadway, engage the required street cleaning components or devices on the other side of the machine and then travel that side of the roadway as necessary to complete his street cleaning operation. Needless to say, the shutting down of one street cleaning operation and the starting up of another street cleaning operation for the opposite side of the machine requires that the operator's attention be directed to street cleaning machine functions, while at the same time he must be aware of traffic conditions and the like. This can become an inefficient and cumbersome procedure particularly if the machine operator is required to continuously transfer from one street cleaning operation to the other.

Vacuum sweepers employ an extension broom in order to sweep a swath wider than that normally accommodated by the pickup nozzle. The extension broom is operated at an acute angle with respect to the transverse axis of the sweeper path and operates to move the sweepings toward the suction nozzle. On dual sweepers, the extension broom must have the capability of sweeping both for right hand and left hand operation and must therefore be mounted so as to swivel so that the angularity of the broom will cause the sweepings to be moved toward the proper pickup nozzle. Heretofore, the extension broom was suspended in such a manner that the broom was held parallel to the level of the truck frame. Inasmuch as a sweeper tends to load up in one side of the hopper, the weight distribution becomes uneven on the truck from left to right. With an uneven load, the truck spring suspension al-

lows the truck frame to drop on one side and with the extension broom rigidly parallel to the truck frame, the engagement of the extension broom bristles with the pavement is heavy on one side and light on the other.

5 This, of course, results in rapid wearing of the broom from a cylindrical shape to a conical shape. After a load has been dumped and sweeping is performed with an empty truck, the cone shaped broom does not have full contact with the pavement. This type of construction, therefore, leads to poor sweeping and short broom life.

Generally, the suction nozzles on a vacuum sweeper are suspended by a movable linkage at the front, for example a parallelogram linkage, and are supported by 15 caster wheels at the rear. The suction nozzles must be lifted before the truck is operated in reverse. Heretofore, the operator has been provided with a switch for raising the suction nozzle prior to operating the truck in reverse. If the operator forgets to raise a suction nozzle, or if the suction nozzle is not raised in time before 20 the truck is operated in reverse and the caster wheels are still on the ground, flat spots on the tires or tires popping off the rim would result.

SUMMARY OF THE INVENTION

25 In view of the evident foregoing disadvantageous constructions of vacuum sweepers and vacuum sweeper control systems, it is a primary object of the present invention to provide a dual vacuum sweeper having an integrated control system which will permit the operator to switch from a street cleaning operation on one side of the machine to a sweeping operation on the other side of the machine by merely operating a single switch.

30 Another object of the invention is to provide an integrated control system for a vacuum sweeper which automatically raises the pickup nozzles in response to the operator shifting the truck into reverse.

35 Another object of the invention is to provide a dual vacuum sweeper having an integrated control system which causes the single extension broom of the sweeper to swivel from left hand to right hand operation, and vice versa, in response to the operation of a single toggle switch which controls the transfer of all sweeping 40 functions from one side of the machine to the other.

45 Another object of the invention is to provide an extension broom for a vacuum sweeper which is maintained parallel to the pavement, wears evenly and has a prolonged sweeping life in spite of uneven loading 50 and weight distribution transversely of the truck.

55 Another object of the invention is to provide a control system for a vacuum sweeper wherein street cleaning functions may be manifest in an alterable program and the program may be selectively effective and the functions provided on either side of a dual vacuum sweeper in response to the simple manipulation of a single switch.

BRIEF DESCRIPTION OF THE DRAWINGS

60 Other objects, features and advantages of the invention, its organization, construction and operation will be best understood from the following detailed description of a preferred embodiment of the invention, taken in conjunction with the accompanying drawings, on which:

65 FIG. 1 is a side elevation of a truck mounted dual vacuum sweeper;

FIG. 2 is a top view of a swivel extension broom employed in the vacuum sweeper of FIG. 1;

FIG. 3 is a sectional elevation of the swivel extension broom construction illustrated in FIG. 2 and taken generally along the line III—III;

FIG. 4 is a partial sectional view of apparatus for pivotally mounting the extension broom for movement about a vertical axis;

FIG. 5 is a fragmentary view of apparatus for pivotally mounting and limiting movement of the extension broom about an axis transverse of the machine;

FIG. 6 is a fragmentary sectional view showing the pivoting movement of the apparatus of FIG. 5 in greater detail;

FIG. 7 is a further detail view of the apparatus of FIG. 5 taken generally along the line VII—VII of FIG. 6;

FIG. 8 is a fragmentary pictorial view of the side broom and vacuum nozzle apparatus as it relates to the frame of the truck;

FIG. 9 is a schematic electrical diagram illustrating an integrated control system having means for programming the operation of the sweeper and means for transferring the effect of the program from one side of the sweeper to the other;

FIG. 10 is a more detailed schematic illustration of relay apparatus employed in the circuit of FIG. 9; and

FIG. 11 is a schematic diagram of the pneumatic system utilized in conjunction with the control system of FIG. 10.

DESCRIPTION OF THE PREFERRED EMBODIMENT

Referring to FIG. 1, a vacuum type sweeper is generally illustrated at 10 as comprising a truck 11 having a set of rear wheels 12 and a set of front wheels 13 supporting the sweeper. The truck 11 is provided with an operator's cab 14 which houses, in addition to an operator, a control console for controlling the street cleaning operations of the sweeper.

The particular sweeper illustrated is a dual sweeper which includes street cleaning apparatus or devices 15 carried beneath and on both sides of a truck frame 16 for carrying out sweeping and vacuuming street cleaning operations or functions. A hopper 17 is provided for receiving sweepings which may be moved from the pavement by way of an extension broom 18, a side broom 19, a suction nozzle 20 and a hose 22. Suction is provided by apparatus mounted forward of the hopper, such apparatus being well known in the art and not discussed in detail herein.

Inasmuch as the illustrated sweeper is a dual sweeper, a second side broom and a second suction nozzle are mounted on the other side of the sweeper. The nozzle 20 is supported by a trailing wheel 21, as is the corresponding nozzle on the opposite side of the machine. While the side brooms and suction nozzles are provided in duplicate, the extension broom serves both sides of the sweeper and is therefore pivotally mounted for movement toward the side of the sweeper which is performing a sweeping operation.

Referring to FIGS. 2-7, the extension broom 18 is illustrated as comprising a weldment or frame 23 which is pivotally connected at its rear portion at 25 to a plate 26 which is connected by a pair of angle members 27 and a pair of angle members 28 to the vehicle frame 16. At its forward end the frame 23 includes an arcuate member 29 which is supported on a pair of angle

shaped members 30 connected to the frame 16 by way of depending members 32 and 33. A plate like member 31 is secured to the member 32 spaced from the member 30, whereby the members 30 and 31 embrace the arcuate member 29. As is common practice, a flexible dust shield 34 is suspended from the frame 23 forward of the rotating broom.

The extension broom 35 comprising one of the street cleaning devices is supported by pins 36 for rotation by a motor 55. A pair of arms 37 support the pins 36 at the forward ends thereof and are connected to a pivot mechanism 38 at the rear ends thereof. An air cylinder 39 is fixed to the frame 23 at 40 and has an extensible member 41 which is connected by a link 42 to a member 43. The member 43 is connected between the arms 37 at a point which divides the arms 37 into two portions, 24 and 52. It is readily apparent that operation of the cylinder 39 moves the extension broom 35 between the transport and sweeping positions.

In FIG. 2 the frame 16 has a pair of transverse frame members 44. A longitudinally disposed member 45 is connected to the members 44. A vertically disposed angle member 46 depends from the member 45 and carries a plate 47. A cylinder 48 is pivotally secured to the plate 47 at one end and includes an extensible member 49 which is pivotally connected to a member 51 of the extension broom frame 23. Operation of the cylinder 48 therefore positions the extension broom for sweeping in cooperation with the left side broom or the right side broom against the respective stops 56, 57. Upon operation of the cylinder 48, the broom frame 23 is pivoted about the pivot 25 and the arcuate member 29 supports the forward end of the frame 23 in a sliding relationship upon the member 30.

Referring to FIG. 4, the pivot 25 is illustrated in greater detail. The plate 26 includes a bore 58 which has a pin 59 welded therein so as to extend below the lower surface of the plate 26. The frame 23 includes a plate 60 having a bore 61 therein which has a ring 62 welded thereto. The inner diameter of the ring 62 is provided with a sleeve 63 which receives the pin 59. The pin 59 includes a threaded bore 64 for receiving a bolt 65 by way of a washer 66 and a washer type bushing 67. As can be seen in the drawing, the ring 62 engages and moves with respect to the sleeve 63 and the bushing 67, while the pin 59, the washer 66 and the bolt 65 are located together by a pin 68 so as to remain stationary with respect to the vehicle frame.

Referring to FIGS. 5-7, the mechanism for maintaining the axis of rotation of the extension broom parallel to the swept surface is illustrated in greater detail. In FIG. 5, it can again be seen that the arm 37 includes a forward portion 24 for connection to the broom and a rear portion 52 for connection to the pivot 38. Each of the arms 52 rotatably receives a respective pin 54. The pins 54 are connected to opposite ends of a tube 89. The extension broom is therefore pivotal about the longitudinal axis of the tube 89. The tube 89 has connected thereto an arm 70 which carries an adjustable stop mechanism 71 for striking a cooperable member 72 carried at the rear end of the arm portion 52 for adjustably limiting the downward movement of the broom to prevent excessive bristle contact and wear. The air cylinder rod length and stroke limits the up position of the broom.

The frame 23 includes a pair of spaced vertically disposed member 73 and 74 having aligned bores 76 and

77, respectively. The members 73 and 74 are in the form of plates and are connected between a pair of plates 75 and 90. A member 79 is secured to the plate 74 and includes a bore 78 which is aligned with the bores 76 and 77. The aligned bores receive a pin 80 which has a transverse bore 82 which may be aligned with a bore 81 of the member 79 for receiving a cotter pin 83 or the like.

The elements 75-81 are located at the center of the tube 89 and, as illustrated in particular in FIG. 7, form a second horizontal axis of rotation for the extension broom generally longitudinally of the sweeper at the pin 80. The plates 75, 90 include respective recesses 91, 92 for permitting a certain amount of rotation about this longitudinal axis. The tube 89 includes a transverse bore at its center for receiving a cylinder 85 having a longitudinal bore 88 for receiving the pin 80. The bore 88 is countersunk at its ends to seat and be partially defined by a pair of bearing sleeves 86 and 87.

The foregoing structure permits pivotal movement of the extension broom about a pair of generally horizontal axes. The first horizontal axis is the longitudinal axis of the tube 89 and the second horizontal axis is the axis of the pin 80. Therefore, in response to changes in transverse and longitudinal slope of the pavement, the extension broom pivots so as to maintain its axis of rotation at the pins 36 parallel to the pavement.

Referring now to FIG. 8, the side brush and suction apparatus for the right hand side of a sweeper is illustrated. Inasmuch as a dual sweeper is disclosed herein, similar apparatus is provided on the opposite side of the sweeper as indicated by the elements 102, 104, 106 and 109. A transverse sub-frame 93 is connected across the vehicle frame 16 and has connected thereto a pair of plates 94 which extend toward the outside of the sweeper. A safety pin 95 may be inserted between the plates 94 and through an upwardly extending member 110 of a side broom weldment or frame 96. The frame 96 includes a transverse bar 99 which is connected to a pair of guide arms 100. Although not illustrated in the drawing, the guide arms terminate in a pivot mechanism similar to that formed by the elements 94, 95 and 110. The member 110 has a stop pin 98 extending therefrom for abutting the bottom edge of the plates 94 to limit upward movement of the side sweeping apparatus.

The sub-frame 93 carries a cylinder 101 which has an extensible member 103 pivotally connected to a lever 105. The lever 105 is pivoted at one end by means of a pin 107 and is pivotally connected at its other end to a member 97 which is similarly attached to the member 110. The member 97 may advantageously be in the form of a cable or rod. Removal of air pressure from cylinder 101 causes the frame 96 to drop down and out due to gravity to lower the side sweeping equipment between transport and sweeping positions; the opposite action being effected upon application of air pressure.

The suction nozzle 20 is of generally known construction and is supported on the surface to be swept by a trailing wheel 21. The suction nozzle 20 comprises another of the street cleaning devices and is connected to and raised and lowered with the frame 96 by means of members 113. The nozzle 20 carries a cylinder 114 having a parallelogram linkage 115 connected to a side broom motor bracket 111. The motor bracket 111 mounts a motor 112 which is connected to and serves to rotate the side broom 19. Operation of the cylinder

114 is therefore effective to raise and lower the side broom 19.

Interposed in the hose 22 between the nozzle 20 and the hopper 17 is a gate valve 118 which is operated by 5 a cylinder 119. In addition, the suction nozzle 20 includes a shutter 116 which is connected to and opened and closed by means of a cylinder 117.

10 Although the foregoing side sweeping apparatus is of generally conventional design, the control of such apparatus, particularly on a dual sweeper, is unique and will be best understood from the following description of FIGS. 9-11.

15 Referring first to FIG. 11, the pneumatic circuit for the sweeper disclosed herein is illustrated in schematic form. The circuit comprises a compressor 123 and a pressure tank 124 which are mounted forward of the hopper 17. The pressure tank has connected thereto a relief valve 125. The pressure tank 124 feeds a pair of main pneumatic lines 126 and 127. The line 126 is associated with the left hand side of the sweeper and with the extension broom and the line 127 is associated with the right hand side of the sweeper. The line 126 is connected in common to a plurality of electrically controlled valves 128-133 which respectively control operation of the left hand shutter cylinder 122, the left side broom cylinder 121, the left hand nozzle lift cylinder 102, the left gate valve 120, the extension broom swivel cylinder 48 and the extension broom lift cylinder 39. The line 127 is likewise connected to a plurality of 20 electrically controlled valves 134-137 for controlling the right hand shutter cylinder 117, the right side broom lift cylinder 114, the right hand nozzle lift cylinder 101 and the right gate valve 119. The valves 128-133 and 134-137 are electrically controlled air valves and the operation thereof is controlled by the 25 circuit of FIG. 9.

30 Referring to FIGS. 9 and 10, an electrical schematic diagram of the circuits for controlling street operations is illustrated as comprising a battery 146 having a negative terminal connected to ground and a positive terminal connected to the ignition switch 147 of the sweeper. The ignition switch 147 includes an accessory terminal 148 which serves to provide positive battery potential to the remainder of the circuit of FIG. 9. An 35 eight pole double throw relay 149 includes a relay winding 150, a plurality of terminals 151L-158L connected to the left side street devices, a plurality of terminals 151R-157R connected to the right hand street devices and a plurality of terminals 151-158 which are connectable to either the left or right hand terminals by 40 corresponding switch contacts 161-167 (FIG. 10). The relay 149 has its contacts 161-167 normally connected in circuit with one set of terminals 151R-157R, for example, when the winding 150 is not energized, and connected in circuit with the terminals 151L-157L, for example, when the winding 150 is energized. The winding 150 is connected between ground and the accessory terminal 148 by way of the relay terminal 158 and a left 45 hand-right hand section switch 182. Therefore, upon operation of the switch 182 the movable contacts 161-167, shown connected at 160 in FIG. 10, transfer to the terminals 151L-157L.

50 The terminals 151L and 151R have respective side broom lights 141 and 138 connected thereto for providing light during night street operations. The terminals 152L, 152R connect to nozzle water spray valves 142 and 139. Similar water spray valves 143 and 140

associated with the side brooms are connected to the respective terminals 153L and 153R. The aforementioned valves 128-131 and 134-137 for controlling the air supply to their respective cylinders are respectively connected to the terminals 154L-157L and 154R-157R. It should be noted that the extension broom swivel control valve 132 is connected to the terminal 158 for receiving energizing power when the switch 182 is closed. The extension broom is therefore biased toward one side of the sweeper and moved toward the other side of the sweeper in response to closure of the switch 182. In addition, the extension broom lift control valve 133 is not connected to the relay 149 inasmuch as transfer of street cleaning operations from one side of the roadway to the other does not necessitate lifting of the extension broom, although this operation may be performed as will be understood from the following description. An electrically operated hydraulic valve 144 for controlling extension broom rotation by means of the motor 55 and a side broom rotation control hydraulic valve 145 are provided. The valve 144 is commonly connected with the extension broom lift control valve 133 and the side broom rotation control valve 145 is connected to the terminals 155L and 155R to control the direction of hydraulic fluid to one side broom or the other in response to operation of the switch 182. All of the above described lights and valves correspond to street cleaning functions including illumination, spraying, lifting and lowering, gating, swiveling and controlling rotation. These functions may be individually selected and stored by means of a plurality of switches mounted in a single switch console 173.

The switch console 173 includes switches 174-181 which, with the exception of the switch 179, are commonly connected to the accessory terminal 148. The switch 175 is operable to store the side broom water spray function and extends positive potential to the terminal 153. The switch 176 is operable to extend positive potential to the terminal 152 and store the street cleaning function of nozzle water spray. The switch 177 stores the illumination function and is connected to the terminal 151. The switch 178 stores the side broom lift function and is connected to the terminal 155. The switch 180 may store the shutter lift function and is connected to the terminal 154. The switch 181 stores the extension broom lift function and is connected directly to the extension broom lift valve 133 as indicated above. Generally, the console 173 is a street cleaning function programmer and the switches thereof are operable to store street cleaning sweeping functions. These functions are transferred into street cleaning operations upon transfer of the relay contacts 161-167 to energize the selected street cleaning control valves, or lights, as the case may be.

The switch 174 is extended to the terminal 156 for automatically controlling the nozzle lift. A relay 172 is interposed between the switch 174 and the terminal 156, the relay being controlled in the backup lamp circuit of the sweeper. A backup light switch 170 is associated with the transmission shifting mechanism of the sweeper and is operable to close and extend positive potential from the accessory terminal 148 to the relay 172 and the backup light 171 upon operation of the relay 172, with the switch 174 closed, positive potential is interrupted to the terminal 156 by the relay 172 to automatically lift the nozzle which is performing a

street cleaning operation at the time. This feature prevents inadvertent or tardy lifting of the nozzle by an operator and the attendant damage which may be caused to the nozzle apparatus as mentioned in the initial portion of the specification.

The sweeper includes a wandering hose 183 (FIG. 1) which is connectable in communication with the hopper 17 and which is used for picking up leaves, etc. at locations several feet beyond the curb. In order to provide sufficient suction for the wandering hose, it is necessary to close both gate valves 119, 120. Heretofore, this has been accomplished by hand in an operation wherein the operator manually closes each gate valve and opens the valving for the wandering hose. In this circuit the switch 179 provides simultaneous operation of both gate valves from the cabin that the switch 179 permits connection of the gate valve on one side of the sweeper to the terminal of the relay normally associated with the gate valve. It will be noted in FIG. 9 that the gate valve 137 is connected to the terminal 157R and to one side of the switch 179, and the gate valve 131 is connected to the terminal 157L and to the other side of the switch 179. Therefore, closure of the switch 179 automatically causes closure of both gate valves.

Although we have described our invention by reference to particular illustrations of a preferred embodiment thereof, many changes and modifications of our invention may become apparent to those skilled in the art without departing from the spirit and scope of the invention. We therefore intend to include within the patent warranted hereon all such changes and modifications as may reasonably and properly be included within the scope of our contribution to the art.

What we claim is:

1. In a vacuum type sweeper of the type wherein a container for receiving debris is mounted on a truck in communication with a suction nozzle which depends from the truck and is movable between a raised transport position and a lower street cleaning position, the truck having shiftable transmission means for conditioning the truck for forward and reverse movement, in combination therewith the improvement comprising means connected between said transmission means and said suction nozzle operable to automatically move said suction nozzle between the street cleaning and transport positions in response to shifting of transmission means between forward and reverse.

2. The improvement set forth in claim 1 wherein said automatically operating means comprises an electrical switch connected to an electrical supply and operated by the transmission means, an electrically actuated device for raising and lowering the suction nozzle, and a relay connected between said switch and said electrically actuated device.

3. A vacuum type sweeper comprising: a truck having a frame and a transmission shiftable between forward and reverse; a pair of side brooms mounted on opposite sides of said truck; side broom control means operable to move said side brooms between sweeping and transport positions; a rotatable cylindrical extension broom; mounting means mounting said extension broom beneath said truck, said mounting means including means for pivoting said extension broom between selected positions where it is cooperable in sweeping toward said side brooms; a pair of suction nozzles mounted on opposite sides of said truck adjacent said side brooms; means for moving said suction nozzles between sweep-

ing and transport positions; a debris container carried by said truck in communication with said suction nozzles; a pair of gate valves disposed between respective ones of said nozzles and said debris container and means for selectively operating said gate valves to interrupt the communication thereof; additional devices in corresponding pairs mounted on opposite sides of said truck and means for operating said devices to perform other street cleaning functions; means operable to store a selection of street cleaning functions connected to said side broom control means, to said extension broom pivoting means, to said means for moving said suction nozzles, to said means for selectively operating said gate valves, and to said means for operating said additional operating devices, and a single switch for causing said devices corresponding to said selection of functions to be placed in operation on one side of the truck; and means connected between said transmission and said means for moving said suction nozzles being operable to cause said nozzles to be raised automatically upon shifting of said transmission into reverse.

4. In a vacuum type sweeper of the type which has sweeping devices mounted on each side thereof capable of performing the same sweeping operations on either side of the sweeper; a pivotal extension broom for sweeping on either side of the sweeper, and control means for controlling operation of said sweeping devices and extension broom and the sweeping position of the extension broom, the improvement wherein said control means comprises: first means for recording a selection of ones of said sweeping devices on each side of the sweeper and said extension broom for operation; second means operable to transfer operation of said extension broom and the selected sweeping devices from one side of the sweeper to the other; and third means including a single switch operable to cause said second means to effect the transfer.

5. In a dual vacuum type sweeper of the type having sets of corresponding street cleaning devices mounted on opposite sides of a sweeper truck for performing street cleaning operations including water spraying and moving brooms into street cleaning positions and transport positions, and control means for controlling said street cleaning devices, the improvement wherein said control means comprises: means for selecting a plurality of street cleaning operations including means for preparing selected devices of corresponding function for operation; and a single control means operating through a switch activated relay operable to place the corresponding devices in operation on a selected side of the sweeper truck and returning the opposite side to a non-street cleaning condition.

6. A control system for a vacuum type sweeper having corresponding sets of street cleaning devices mounted on opposite sides of a sweeper truck for performing the same street cleaning functions on each side of the truck; said control system comprising; a first plurality of control devices connected to the street cleaning devices on one side of said truck and operable to control the operation of the respective street cleaning devices; a second plurality of control devices connected to the street cleaning devices on the other side of said truck and operable to control the operation of the respective street cleaning devices; function selection means connected to said first and second pluralities of control devices for selecting corresponding devices on each side of the truck for operation in accordance with corresponding desired street cleaning functions; and side selection means comprising a single control connected to said function selection means for effecting operation of the selected devices to cause operation of the associated street cleaning devices on either side and returning the opposite side to a non-operative transport condition.

5

7. A control system for a vacuum type sweeper having a plurality of first street cleaning devices for performing individual street cleaning operations mounted on one side of the sweeper truck and a plurality of second street cleaning devices for performing individual street cleaning operations corresponding to the street cleaning operations of the first street cleaning devices and mounted on the opposite side of the sweeper truck, said control system comprising: a plurality of first and second control devices connected to respective ones of said first and second street cleaning devices for operating the respective street cleaning devices; means for selecting the operational state of said street cleaning devices; and a single control means operating through a switch activated relay for transferring operation of said selected ones of said first or second control devices so that a desired combination of street cleaning operations may be transferred from one side of the sweeper to the other and returning the opposite side to a non-street cleaning condition.

10

8. A control system according to claim 7, wherein said means for selecting the operational state includes a plurality of switches connected to an electrical supply and each controlling the operation of a selected street cleaning device, and said means for transferring operation of said selected control devices includes relay means connected to said first and second control devices and to an electrical supply via said plurality of switches, and a further switch connected between the electrical supply and said relay means and operable to cause said relay means to transfer connection of said first and second control devices alternately to the electrical supply via said plurality of switches.

15

9. A control system according to claim 8, comprising a transmission operated switch and a second relay means operated thereby, and wherein particular ones of the street cleaning devices on each side of the sweeper truck is operable to raise and lower respective suction nozzles, and wherein said control devices corresponding to the particular nozzle raising and lowering devices are further connectable to an electrical supply via said second relay means in response to shifting of the transmission into reverse to automatically lift the suction nozzles.

20

10. A control system according to claim 8, wherein said relay means includes a first set of contacts connected to said first control devices, a second set of contacts connected to said second control devices, a set of movable contacts connected to said plurality of switches and normally contacting said first set of contacts, and winding means connected to said further switch to be energized and de-energized thereby to transfer said set of movable contacts between said first and second sets of contacts.

25

11. A vacuum sweeper comprising:
a wheeled vehicle for movement along a surface to be swept, said vehicle including a frame and a transmission shiftable by an operator between forward and reverse;
street cleaning devices including;

a pair of side brooms connected to opposite sides of said frame for movement between street cleaning and transport positions, and means for moving said side brooms individually between said positions; a pair of suction nozzles connected to said frame to 5 the rear of respective ones of said side brooms for movement between street cleaning and transport positions, means for moving said nozzles individually between said positions, and means connected between said nozzles and said transmission for automatically raising said nozzles in response to shifting of said transmission into reverse; extension broom means pivotally mounted to and beneath said frame including a rotatable extension broom, means for maintaining the axis of rotation of said extension broom parallel to the swept surface, and means for pivoting said extension broom 10 between positions where it is cooperable with the respective side brooms to extend the width of 15

sweeping swath on each side of the sweeper; sweeping control means connected to said means for moving said side brooms and said nozzles and said means for pivoting said extension broom being operable to transfer operation of said street cleaning device from one side of the sweeper to the other; and

a hopper carried on said frame and connectable in communication with said suction nozzles.

12. A vacuum sweeper according to claim 11 comprising a pair of individually operable electrically controlled gate valves disposed between respective ones of said suction nozzles and said hopper; and a wandering hose connectable in suction communication with said hopper, and wherein said sweeping control means includes a switch connecting both of said gate valves to an electrical supply for concurrent closure when said wandering hose is to be used.
